UNITED STATES PATENT OFFICE.

WILLIAM SCHELLENBACH, OF HARTWELL, OHIO.

GEARING.

1,074,819.

Specification of Letters Patent.

Patented Oct. 7, 1913.

Application filed October 28, 1912. Serial No. 728,326.

To all whom it may concern:

Be it known that I, WILLIAM SCHELLENBACH, a citizen of the United States, residing at Hartwell, in the county of Hamilton and 5 State of Ohio, have invented certain new and useful Improvements in Gearing, of which the following is a specification.

This invention relates to improvements in speed change gearing as of the type used in 10 machine tools, and it deals with an organization and modification such that, notwithstanding the provision of a very compact structure, the range of speed changes may be greatly extended and their selection facilitated.

One object within the contemplation of this invention is to intervene between the lead screw and spindle of a lathe a cone of gears, as well as certain other speed change and 20 reverse gearing, and to do so in such a manner that a high order of durability, compactness and convenience will be insured.

Another object is to utilize and incorporate in the combination of the herein specified 25 elements, the underlying principles and gist of construction of the English-metric change system specified in my copending application Serial No. 728,327, filed of even date herewith, and at the same time to effect certain improvements therein tending to as 30 high an order of simplicity and compactness as may be consistent with the extended capacity of the invention.

Another object is to effect an improvement 35 in the cone gearing organization, such that the same will consist of fewer parts than have heretofore been employed, and will be noteworthy for an enhanced strength and sturdiness in the parts.

Another object is to render available a 40 gear box, in the form of a unitary structure, which would be characterized by an extended range of speed changes, while at the same time enabling a shift from an English to a metric standard.

Other objects and advantages will be in part pointed out in the following description, and in part rendered apparent therefrom in connection with the drawings accompanying this disclosure.

In order that this invention may be so fully disclosed to those skilled in this art that they may be enabled to embody the same in the various forms and modifications

to which it is readily subject, drawings exemplifying a preferred form have been appended as a part of this disclosure, and in such drawings, like characters of reference denote corresponding parts throughout all of the figures, of which:—

Figure 1 is a front elevation showing a structure embodying the features of this invention assembled and applied to a lathe. Fig. 2 is a vertical section taken transversely along line 2—2, of Fig. 1, showing the gears used for evaluating the ratio of the system to enable metric threads to be cut when such gears are operatively connected with the organization. Fig. 3 is a section taken transversely through the gear box along line 3—3 of Fig. 1, showing certain details of an arrangement for connecting in and out a speed change compound gearing. Fig. 4 is a section taken transversely through line 4—4, of Fig. 1, showing the arrangement of the lever that operates to connect and disconnect the ratio evaluating gearing from the system when it is desired to change from English to metric cutting, or conversely. Fig. 5 is a section taken along line 5—5, of Fig. 1 showing more clearly the mounting of the tumbler gear lever and parts connected therewith, whereby the same is more rigidly mounted than heretofore, and certain strains are removed from the shaft from which the tumbler gear is usually driven. Fig. 6 is an end elevation of the head stock and bed of a lathe showing the arrangement of the reverse mechanism and other compounding gears and also showing the location of the interchangeable gear that is used when the system is changed from English to metric, or conversely. Fig. 7 is an upright section following line 7—7 of Fig. 6, showing in cross section the relation of the reversing gearing and the compounding gearing at the end of the head stock. Fig. 8 is a horizontal section taken along line 8—8, Fig. 6, showing in general assembly the first compound gears, the cone of gears and tumbler organization, as well as elements of the metric-English change mechanism. Fig. 9 is a partial elevation of the gears at the end of the head stock, together with a section taken through line 9—9 of Fig. 6.

Continuing now by way of a more complete disclosure of the underlying principles

and features of this invention, it may be stated that the description, while directed largely to specific details, is to be taken in an illustrative or explanatory sense, rather than in a limiting sense, inasmuch as the features of the invention may assume different forms from that shown, as will be readily comprehended by those skilled in the art in the light of this disclosure.

10 By way of example, the invention has been shown applied to that type of machine tools known as an engine lathe. The end of the lathe bed is indicated by 1 on Fig. 6 and, arranged on appropriate guides thereof, is the head-stock indicated by 2. In this head-stock is journaled a spindle 3 that carries the gear 4 at its left hand end. Mounted on an appropriate portion of the head-stock, preferably directly underlying the spindle, as shown by Fig. 7 is a bearing piece 5, on the end of which is pivoted a plate 6, having an operating handle 7, shown more clearly by Fig. 6, that serves to shift the same for reversing purposes as will presently be made apparent. This shift plate carries a pivot pin 8 on which is journaled the direct motion gear 9 that meshes with the gear 4 when the plate 6 is positioned, as shown by Fig. 6. A second gear 10 permanently meshes with the gear 9 and is also carried on the plate 6 by means of the pivot pin 11, so that when the plate 6 is swung upwardly by the handle 7, the gear 9 will be disconnected from gear 4 and the gear 10, 25 which normally acts as an idler, will now be brought into mesh with gear 4, and thus serve as a means instrumental in reversing the direction of gear 9, without, however, varying its rate of movements relative to gear 4. Within the aforesaid bearing piece 5 is journaled a shaft 12 that terminates at its left hand end in a gear 13; a wide face gear 14 being also keyed to the shaft 12 in permanent mesh with gear 9, so that it is 30 constantly rotated and in turn also constantly rotates the shaft 12 and the gear 13.

Turning now to Fig. 8, 15 indicates a stationary bearing block mounted in fixed relation with the bed of the lathe, as by means 35 of the lug 16, bolted to the casing of the tumbler gear box, which is in turn bolted to the bed of the lathe. Through this stationary block 15 is arranged a bearing pin 17 that at its ends pivotally carries the cage 18, in 40 which is mounted certain compound gears, as will be presently described. This cage, together with said gears, is adapted to be rocked by the handle 19 at the end of the arm 20 and a bolt 21 serves to lock the same 45 in such position as it may have been placed.

Journalized in the cage 18 is a pin 22 on which is keyed a small gear 23 and on which is slidably splined a large gear 24. This gear 24 is adapted to be set into any one of 50 three positions by means of the finger piece

25, for the purpose of enabling three speed changes to be effected at this point, as will now be explained.

Referring to Fig. 7, it will be observed that gear 24 is shown in mesh with gear 14. This indicates the extreme right hand position of gear 24 and gives the first speed. If the finger piece 25 be pulled out to shift the gear 24 into a plane coincident with that of gear 13, then by swinging lever 19, these two gears may be approached and caused to mesh, thus yielding the second speed. Now, if the gear 24 be moved to its extreme left hand position it will entirely clear gear 13 and by swinging the lever 19 further, the gear 23 may be brought into mesh with gear 14, giving the third speed of the system. These speeds are transmitted to the gear box 27 containing the cone of gears and the metric-English change system by means of the intermediate gear 26 that is journaled on the spindle block 15 and constantly meshes with gear 23.

The gear box 27, together with its contained elements, is preferably constructed 90 in the form of a structural unit and it is bolted to the main frame or bed of the machine in a suitable manner. In describing this arrangement, it will be convenient first to follow the order shown in the accompanying drawings, wherein the elements are arranged to cut English threads.

In cutting English threads the motion from the gear 26 is transmitted by the gear 28, shown in this instance keyed to the end 100 of an elongated gear 29 that has a bearing in the wall of the gear box 27 and is also rotatably journaled on a shaft 30; whose right hand end is fixed to gear 31, which is in turn fixed to the lead screw 32, and is also journaled in the frame of the gear box 27. The gear 28 is held on the sleeve of the gear 29 by means of a removable pin or slotted washer, so that it readily may be taken off and interchanged in position on another 110 shaft, and at the same time maintained in mesh with the driving gear 26. In the mounting shown in the drawings, the elongated gear 29 is, of course, suitably driven independently of any rotary motion possessed by the shaft 30, by reason of its connections through the gear 28. By a suitable tumbler arrangement, this motion is in turn directly transmitted to the selected one of any of the gears A, B, C, etc., which constitute a cone of gears, each of which insures a rate of movement in this direct drive corresponding to any one of a predetermined series of pitches of standard English threads.

120 By the form of tumbler mechanism here disclosed, an aim has been made to transmit a considerable amount of power for high duty work, without imposing any more strain than is necessary on the shaft 30. To 130

this end, the tumbler mechanism is carried directly from the frame of the gear box 27 and provision is made whereby it will swing about a center coincidental with the axis of 5 the shaft 30.

Referring to Figs. 4, 5 and 8, 33 and 34 indicate lower and upper horizontally extending guide ways provided by the gear box and, mounted to slide laterally on these 10 guide ways, is a traveling block 35. This block in turn provides a circular guide way 36 that is curved about a center coincidental with the axis of the shaft 30. A tumbler gear support 37 is in turn fitted 15 to the circular segment guide 36, and by means of an operating handle 38, it may be moved up and down on the traveling block 35, and it may be shifted laterally by sliding the block 35; the whole moving as a 20 unit. The tumbler gear support 37 carries a pin 39 on which is journaled a tumbler gear 40 and, from the foregoing, it will be perceived that this gear 40 will constantly mesh with the gear 29 irrespective of any 25 position of the handle 38. To enable the operator, however, to bring gear 40 into proper mesh with any one of the gears A, B, C, etc., a plate 41 is secured to the gear box and such plate provides a series of in- 30 ternal grooves indicated on Fig. 1 by dotted lines 42, and it also provides an external series of holes A', B', C', etc., corresponding to the respective gears of the cone of gears. The arm of the tumbler gear support carries a key 43, which may be brought to enter any one of the grooves 42, thus insuring that the tumbler gear 40 will be brought 35 in the same radial plane as that of the selected gear and by continuing the swing of the arm 38, the pin 44, carried thereby will enter one of the series of holes and thus accurately determine the proper relation of 40 the pitch lines of the gears. Motion may be thus transmitted from the gear 29 to any 45 one of the cone of gears and, as the latter are all keyed to a shaft 45 journaled in the gear box, such shaft will be rotated at a rate depending upon which of the gears A, B, C, etc. is in mesh.

50 A description will now be given of the means whereby the motion of the cone gear shaft 45 may be transmitted to the lead screw 32 through a compound gearing enabling a series of further speed changes to 55 be made, fixed to the end of the shaft 45 is a collar 46 that provides a clutch 47. Journaled on the shaft 45 is also a sleeve 48 that is normally free to rotate independently of such shaft, and which, when in the position 60 shown by Fig. 9, may be locked to rotate with said shaft by means of the clutch 47. In this position, therefore, this sleeve 48 acts as though fixed to the shaft 45, and it in turn is telescoped by a sleeve 49 that is 65 splined thereto, and is rotatably retained

against lateral shift by its mounting in the bearing 50 on the gear box. This sleeve 49 also provides the smaller gear 51, the intermediate 52, and the larger gear 53; any one of which may be brought into operative connection with the lead screw. To enable this to be accomplished, the sleeve 54 is rotatably journaled on the shaft 30 and terminates at its right hand end in clutch 55 that now meshes with a corresponding clutch on the gear 31, so that when the sleeve 54 is driven, it will, through the gear 31 drive the lead screw 32. Keyed onto the sleeve 54 is a second sleeve 56, on which in turn is splined a gear 57 having the clutch 58 at its right hand end as well as the clutch 59 at its left hand end. Any motion transmitted to the gear 57 will therefore positively drive the shaft 30 through the sleeve 56 and sleeve 54. In the position shown by Fig. 9, the gear 57 is in mesh with gear 52, and, therefore, the shaft 30 is driven at a rate corresponding to the ratio between the last mentioned gears. Means is provided, however, whereby the gear 57 may be slipped laterally, unmeshed from gear 52 and engaged to be driven either by the gear 60 or the gear 61. This is accomplished by means of the yoke block 62, having a rack 63 in its upperface in mesh with the teeth on a pinion 64, which may be actuated from the front of the gear box by the thumb nut 65. This actuating member 62 slides on the bearing surface 66 of the gear box and preferably carries an index point 67, to show the operator which of the gears are in mesh, *i. e.* what speed ratios will prevail.

It will be observed that in the position shown the gears 60 and 61 revolve idly, but when gear 57 is moved, say to the left, the clutch 59 will engage with a counter part member on the gear 60, so that the gear 53, which is in constant mesh with gear 60, will now become the driven gear and the shaft 30 will be rotated at a speed corresponding to the ratio now prevailing. In like manner, the gear 51 constantly meshes with gear 61 and, should the gear 57 be moved to the right, the clutch 58 will enable gear 61 to actuate the shaft 30.

In cutting metric threads, the gear 28 is interchanged in position and is placed on the end of the shaft 45, which is the same distance as the shaft 30 from the center of gear 26, so that it will first drive shaft 45. The gears A, B, C, etc., are now each first driven, and through the tumbler gear 40 their motion is transmitted to the elongated gear 29, which latter will rotate (independently of the shaft 30) at a rate determined by which 120 of the gears A, B, C, etc., is in mesh. The purpose of driving in reverse order through the gears aforesaid, is to reverse the schedule on the index plate so that the latter may be used in the conventional manner by those

following the practices of the metric system, as has been more fully explained in the above mentioned co-pending application.

In continuing this description, it will be 5 convenient to employ lower case alphabetical characters in denoting the parts other than those mentioned in the foregoing, so as more clearly to differentiate the functions of the elements peculiar to the metric system.

10 Referring to Fig. 4, the mounting of a system change lever *a* will be rendered apparent. This lever projects from an upwardly extending rock shaft *b* that is journaled in this instance at the back of the gear box and carries upper and lower rack sleeves *c* and *d*, both of which are keyed to the shaft *b*. The upper rack sleeve *c* meshes with a collar *e*, (see Fig. 8) that is journaled on the sleeve 54, so that by moving 15 the lever *a* to the left, the sleeve 54 will be similarly moved and disconnect the clutch 55, and then engage the clutch *f* at the left hand end of the sleeve 54 with a counterpart member on the elongated gear 29. The 20 sleeve 54 is now driven directly from the gear 29, and it will in turn transmit motion through gears 60 and 53, or 57 and 52, or 61 and 51, to sleeve 48, according to the position of the gear 57. So far as explained, the 25 shaft 30 is not connected up to rotate, but when the lever *a* is swung to the left the rack sleeve *d*, through its engagement with the rack gear *g*, will move the sleeve 48 to the left and disconnect the clutch 47. On the 30 right hand end of this sleeve is a gear *h* that now comes into mesh with a gear *k* that is journaled on a pin *l*, as shown by Fig. 8. Fixed to rotate with gear *k* is a companion gear *m* that is in constant mesh with gear 35 31, so that such gear 31 is now driven and as it is keyed to the lead screw the latter in turn will be actuated. It may be noted that the gears *h*, *k*, *m*, and 31 constitute a ratio evaluating gearing which introduces 40 the proper constant into the system so that movements in accordance with the metric 45 pitches now will be transmitted.

It will thus be perceived that this invention is well adapted to achieve the objects 50 and ends above stated by relatively simple and compact organization. The arrangement is such that the index holes A', B', C', etc., which serve for determining the English pitches, will also serve for determining 55 the metric system when the system change levers are operated, and thus the apparatus may be used with equal facility either by those accustomed to English or to metric standards.

60 What I claim and desire to secure by Letters Patent is:—

1. A structure of the nature disclosed combining a first shaft, a gear mounted thereon, a second shaft, a cone of gears keyed there- 65 to, a tumbler gear establishing connection

therebetween, a driven member on said second shaft, a driving member on said first shaft, means for connecting said driving and driven members respectively directly with their shafts, and alternative means for gearing said driving member directly to said second shaft and gearing said driven member to said first shaft. 70

2. A structure of the nature disclosed combining a shaft, a gear journaled thereon and adapted to rotate independently of said shaft, a cone of gears, a tumbler gear for connecting said gear to any one of said cone of gears, and gearing intervening between said cone of gears and said shaft to enable 75 the former to drive the latter. 80

3. A structure of the nature disclosed combining a shaft, a gear journaled thereon and adapted to rotate independently of said shaft, a cone of gears, a tumbler gear for connecting said gear to any one of said cone of gears, and speed change gearing adapted 85 to establish a driving connection between said cone of gears and said shaft. 90

4. A structure of the nature disclosed combining a shaft, a gear journaled thereon and adapted to rotate independently of said shaft, a cone of gears, a tumbler gear for connecting said gear to any one of said cone of gears, gearing between said cone of gears 95 and said shaft, and a clutch for connecting said gearing with said shaft. 100

5. A structure of the nature disclosed combining a shaft, a gear journaled thereon and adapted to rotate independently of said shaft, a cone of gears, a tumbler gear for connecting said gear to any one of said cone of gears, a sleeve journaled on said shaft, gearing between said sleeve and said cone of gears, and clutch mechanism for enabling 105 said sleeve to be connected either with said first mentioned gear or said shaft. 110

6. A structure of the nature disclosed combining a shaft, a gear journaled thereon and adapted to rotate independently of said shaft, a cone of gears, a tumbler for connecting said gear to any one of said cone of gears, gearing intervening between said gear and said shaft, and clutch mechanism for establishing connection between said gear 115 and gearing and between said gearing and shaft. 120

7. A structure of the nature disclosed combining a shaft, a gear journaled thereon and adapted to rotate independently of said shaft, a cone of gears, a tumbler for connecting said gear to any one of said cone of gears, a speed change system of gears, and means for establishing a driving connection between said first mentioned gear, said system and said shaft. 125

8. A structure of the nature disclosed combining a first shaft, a gear journaled thereon, a second shaft, a cone of gears fixed thereto, a tumbler gear therebetween, an- 130

other gear, a clutch for connecting said gear with said cone of gears, and means for establishing or interrupting an operating driving connection between said other gear and said first shaft.

9. A structure of the nature disclosed combining a first shaft, a gear journaled thereon, a second shaft, a cone of gears fixed thereto, a tumbler gear therebetween, a sleeve journaled on said second shaft, a clutch connecting said sleeve with said shaft, gearing between said sleeve and said first shaft, and clutch mechanism for establishing a connection between said gearing and 15 first shaft.

10. A structure of the nature disclosed combining a first shaft, a gear journaled thereon, a second shaft, a cone of gears fixed thereto, a tumbler therebetween, a sleeve 20 journaled on said first shaft, a clutch for connecting said sleeve with said first mentioned gear, another sleeve journaled on said second shaft, and gearing between said other sleeve and said first shaft establishing 25 driving connection therebetween.

11. A structure of the nature disclosed combining a first shaft, a gear journaled thereon, a second shaft, a cone of gears fixed thereto, a tumbler therebetween, a sleeve 30 journaled on each of said shafts, gearing establishing driving connection between said sleeves, and shifting mechanism for connecting the one sleeve with the first mentioned gear and the other sleeve in driving connection 35 with said first shaft, or for connecting both sleeves to their respective shafts.

12. A structure of the nature disclosed combining a first shaft, a gear journaled thereon, a second shaft, a cone of gears fixed 40 thereto, a tumbler therebetween, a first sleeve journaled on said first shaft, a second sleeve journaled on said second shaft, gearing between said sleeves, and means for locking each sleeve to its shaft or for establishing 45 connection to drive said first shaft from said first mentioned gear through each of said sleeves in succession.

13. An apparatus of the nature disclosed combining a casing, a supporting member 50 arranged to slide thereon and having a circular guide segment, an operating lever slidably retained by said segment, a gear pivotally supported on said lever, a shaft arranged with its axis coincidental with the center of curvature of said segment, and a gear on said shaft meshing with said other gear.

14. A structure of the nature disclosed combining a shaft, a cone of gears mounted thereon, a second shaft, a gear supported 60 thereon, means for operatively connecting said gear with any one of the gears of said cone, an actuating gear mounted equidistant from said shafts, and a gear adapted to be interchanged in position from the one 65 to the other of said shafts operatively to connect either of said shafts with said actuating gear.

15. A structure of the nature disclosed combining a shaft, a cone of gears mounted 70 thereon, a second shaft supporting a gear, means for operatively connecting said gear with any one of the gears of said cone, an actuating gear mounted equidistant from said shafts, a power driven spindle, speed- 75 change gearing connecting said spindle with said actuating gear, and a gear adapted to be interchanged in position from the one to the other of said shafts operatively to connect either of said shafts with said actuating gear.

16. An apparatus of the nature disclosed combining a casing, a supporting member arranged to slide thereon and having a circular guide segment, an operating lever slidably retained by said segment, a gear pivotally supported on said lever, a shaft arranged with its axis coincidental with the center of curvature of said segment, and an elongated gear on said shaft meshing continuously 85 with said other gear irrespective of the position of the latter.

17. An apparatus of the nature disclosed combining a casing providing a series of stops, a supporting member arranged to 95 slide horizontally thereon and having an upwardly extending circular guide segment, an operating lever slidably retained by said segment, a catch on said lever adapted to be brought into engagement with any one of 100 said stops, a gear pivotally supported on said lever, a shaft arranged with its axis coincidental with the center of curvature of said segment, and an elongated gear on said shaft restrained against longitudinal displacement and continuously meshing with 105 said other gear irrespective of the position of the latter.

In testimony whereof, I have hereunto set my hand.

WILLIAM SCHELLENBACH.
